(57) **CLAIM**

The ornamental design for a trim for vehicle, as shown and described.

DESCRIPTION

FIG. 1 is a side view of a vehicular pillar trim with "GRAVITY" text, of a first embodiment of the new design; FIG. 2 is a front perspective view of a vehicular front panel with "GRAVITY" text, of a second embodiment of the new design;

FIG. 3 is a front view of the second embodiment;

FIG. 4 is a top view of the second embodiment;

FIG. 5 side view of the second embodiment;

FIG. 6 is a side view of the second embodiment, opposite that of FIG. 5; and,

FIG. 7 is a bottom view of the second embodiment.

The broken lines (including those for the front facia, the front grille, the vehicular body, and the "LUCID" text) are for environmental illustrative purposes only and form no part of the claimed design.
